UNITED STATES PATENT OFFICE.

JOSEPH A. READ AND EDWARD L. CALEY, OF PHILADELPHIA, PENNSYLVANIA, ASSIGNORS TO GILBERT COMBS, JOHN BAWDEN, AND JOHN H. BAWDEN, ALL OF FREEHOLD, NEW JERSEY.

DESIGN FOR A FIRE-PLACE GRATE.

SPECIFICATION forming part of Design No. 16,133, dated June 16, 1885.

Application filed April 30, 1885. Term of patent 7 years

To all whom it may concern:

Be it known that we, JOSEPH A. READ and EDWARD L. CALEY, both citizens of the United States, and residents of Philadelphia, 5 Pennsylvania, have invented or produced a new and original Design for a Grate for Fire-Places, of which the following is a specification.

Our design for a grate for fire-places is fully 10 shown in the accompanying photographic illustration. The back plate of the grate comprises a lower portion of rectangular form and an upper portion with concave ends, each portion having a panel of substantially the 15 same outline, and these panels being ornamented with raised work of a scroll-like character, the details of which are too fully shown to need description. The side plates of the 20 grate are substantially of an L shape, and have panels of the same shape ornamented 25 with scroll-work, the character of which is substantially similar to that on the back plate, with such modifications as are required by the different shape of the side plates. The front 30 bars of the grate have at the ends projecting mushroom-like bosses, and similar bosses are formed upon the front ends of the side plates of the grate and on the center of the upper front bar of the same. The lower front bar 35 of the grate has a central rounded portion, but on each side of the same is made of rectangular form, and grooved or banded, as shown.

The grate has andiron-like extensions in 40 front, these extensions terminating in ornamental feet.

We claim—

1. In a design for a fire-place grate, the design for the back plate, said design consisting of the lower rectangular portion, with panel 40 ornamented with raised work of scroll-like character, and the upper portion with concaved ends, and panel with raised scroll-like ornamentation, as shown and described.

2. In a design for a fire-place grate, the design for the grate-casing, said design consisting of the back plate, with its upper and lower portions, with panels ornamented with raised work of scroll-like character, and the L-shaped side plates having panels with similar 50 ornamentation, as shown and described.

3. In a design for a fire-place grate, the design for the grate, said design consisting of the back having upper and lower panels, the side plates with ornamented panels, the front bars, 55 and the projecting mushroom-like bosses at the ends of the bars and at the front ends of the side plates, as shown and described.

4. The design for a fire-place grate, said design consisting of the back having upper and 60 lower panels, the side plates with ornamental panels, the front bars and andiron extensions forming continuations of the side bars of the grate, and having ornamental feet at the front ends, as shown and described. 65

In testimony whereof we have signed our names to this specification in the presence of two subscribing witnesses.

JOSEPH A. READ.
EDWARD L. CALEY.
